IGNITION COIL CONSTRUCTION

Adelbert J. Gogel, Toledo, Ohio, assignor to The
Electric Auto-Lite Company, Toledo, Ohio, a
corporation of Ohio

Application April 20, 1934, Serial No. 721,569

1 Claim. (Cl. 175—361)

This invention relates to electrical apparatus suitable for producing high tension currents and particularly to a transformer or induction coil suitable for use in ignition systems for internal combustion engines.

The invention embraces the provision of a novel and efficient method of insulating the terminals of the windings from each other and from any metallic element.

10 The invention has for an object to provide a transformer construction wherein the connecting means to the windings or the circuit connections thereto are so arranged as to form a substantially hermetically moist-proof unit.

15 Another object of the invention is to provide an improved means for connecting, securing and enclosing the circuit connecting means to the high tension terminal, keeping the connection free from moisture and foreign matter and preventing any condensation adjacent thereto.

20 Another object of the invention is to provide an improved arrangement whereby resilient means are used for properly retaining the circuit terminals and preventing condensation within the coil casing.

25 Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

30 Figure 1 is a top plan view of an ignition coil embodying the present invention;

35 Figure 2 is a longitudinal cross-sectional view taken substantially on the lines 2—2 of Figure 1;

40 Figure 3 is a perspective view showing the coil terminal supporting means and condensation or dust preventing means;

45 Figure 4 is a sectional view taken substantially on the lines 4—4 of Figure 1;

50 Figure 5 is a top plan view of the high tension terminal protecting means shown in Figure 3;

55 Figure 6 is a cross-sectional view taken substantially on the line 6—6 of Figure 5;

55 Figure 7 is a sectional view taken substantially on the line 7—7 of Figure 5.

This invention may be included in any type of high frequency or high tension apparatus, and for a practical application of the principle of the invention I have selected to illustrate the

same as incorporated in a transformer of a particular construction known as ignition coil suitable for use with internal combustion engines. It is understood, however, that I do not wish to limit the principles of the invention to the particular embodiment illustrated and that I contemplate its use whenever the same may be found of utility.

5 Referring to the drawing in detail, the ignition coil illustrated as embodying the invention comprises an outer housing consisting of a tubular member 10, preferably made of magnetic material, closed at one end by base member or plate 12, joined to member 10 by seam 14 which may be interlocked as shown, or soldered, thus forming an open end housing capable of receiving the elements of the coil proper which are assembled as a unit. The coil unit comprises a non-conducting base or supporting member 15 preferably made of porcelain, which is provided with a recessed portion 17 for the purpose of receiving a disc of resilient insulating material 18 and the magnetic core of the coil which, in the present instance, comprises a plurality of thin metallic strips or laminations 20. Surrounding the disc 18 is a 10 tube of insulating material 22 within which laminations 20 are enclosed and upon which is wound the secondary winding 24 of the ignition coil. The secondary or high tension winding 24 consists in the embodiment illustrated of a plurality of convolutions of suitably insulated wire forming layers which in turn are suitably insulated from each other by means of a sheet of dielectric material, preferably paper, this insulating material provides marginal portions 25 and 27 at each 15 end of the layers of the secondary winding 24. The insulating material contacts at one end with the non-conducting member 15 which serves as supporting means for the winding on the coil housing.

20 Surrounding the secondary winding 24 is a tube of insulating material 30, the same being of such dimensions as to snugly fit the outer periphery of the supporting base member 15. On a plurality of layers of insulating sheet material forming a 25 tubular member 30 is wound the primary or low tension winding 33 consisting of a plurality of convolutions or turns of suitably insulated strand material such as wire wound on layers which are separated and suitably insulated by sheet material, the layers of the wire of the primary winding 33 in the present instance being longer than those of the secondary winding 22. The primary winding is in turn surrounded by a plurality of turns of sheet material forming the tubular member 35 30

which rests on the base portion of the coil housing 12 and has a portion projecting at the upper end of the winding forming a margin or projecting portion 36.

- 5 The terminals or connecting leads of the primary and secondary windings, prior to their incorporation within the coil housing, are positively insulated, the primary winding connecting lead 38 being surrounded by a tube 39 of insulating 5 material while the primary connecting lead 42 is surrounded by a tube 43 of insulating material, the high tension lead 45 being surrounded by a tubular member of proper dielectric strength 47. Prior to the incorporation of this unit into the 10 coil housing, a suitable compound is employed in order to fill the voids and prevent any moisture or condensation within the coil housing. In order to provide an efficient unit, the transformer or ignition coil is provided with an external magnetic 15 circuit which comprises a plurality of laminations 49 located within the annular space provided between the insulating tube 35 and the tubular member 10 of the coil housing. The central magnetic core 20 is positively insulated from possible 20 contact with the high tension lead 45 by means of a cap member 50 which cooperates with tubular member 22 thus entirely surrounding the upper portion of the magnetic core 20, which projects above the layers of the windings.
- 25 The other end of the tubular member 10 of the coil housing is adapted to be closed by a cover 52 preferably made of moulded insulating material as a condensation product, the cover is formed with a peripheral metallic annular member 53 provided with a depending flange 54 which tightly 30 engages the outer surface of the tubular member 10 being secured thereto in any suitable way as by soldering as shown at 55 thus forming a moist-proof housing. Cover member 52 is provided with 35 a depending annular wall or flange 57 adapted to accommodate and hold the magnetic core 20 in a central position within the coil housing, in addition annular flange 57 contacts with one end of the insulating sheet material of the high tension 40 windings for holding the same against the base member 15 thus preventing displacement of the winding within the coil housing.

45 Imbedded in the insulating material of the cover member 52 are the terminals of the windings to which the circuit connections or conductors are attached. The low tension circuit or terminals 56 and 58 of the primary winding 33 are carried by suitable bosses 59 and 60 projecting from the outer surface of cover 52. Terminals 56 and 58 are identical in construction 50 and comprise hollow metallic inserts having a threaded portion 61 adjacent to an enlarged portion 64 imbedded in the insulating compound of cover 52. The cover 52 also carries the high 55 tension terminal 66, also formed of a hollow metallic member provided with a threaded portion 68. Adjacent to the high tension terminal 66 is projecting wall 70 of a substantially U-shaped configuration formed on cover member 52, 60 acting as a separating baffle between the high tension terminal 66 and the low terminals 56 and 58. Baffle 70 in addition to the projecting bosses 59 and 60 serves to provide suitable insulation between the terminals preventing any short circuit 65 of the windings by increasing the surface path between the same. Adjacent to the high tension terminal 66 the thickness of the cover member 52 is increased as it is formed with a semi-circular depression or groove 72 for accommodating 70 the high tension connecting cable 73.

The circuit receiving terminals are connected to the end of the windings by passing through the hollow insert of terminal 56 the connecting lead 42 of one end of the low tension or primary winding 33, and the other end of said winding being connected by lead 38 to the metallic insert of terminal 58, to which is also connected the outer end of the high tension winding 24 due to the interconnection of one end of the primary and secondary windings to lead 38 within the insulating tubular member 39. The inner end 10 of the high tension winding being connected to terminal 66 by lead 45 which is surrounded by the flange 57 separating leads 38 and 42 of the low tension windings from the high tension lead 15 45. The leads 38, 42 and 45 are permanently secured to the metallic insert after the cover 52 is in place by soldering the ends to the ends of the terminals thus positively closing their openings and providing a good electrical connection 20 between the terminals and the windings.

25 Before the housing cover 52 is placed in its final position and prior to soldering the leads of the windings to the terminals a sufficient quantity of insulating compound is poured within coil 25 housing to bring the level nearly to the top of tubular member 10 then the cover is permanently secured to the coil housing and the leads are soldered to the terminals, carried by the cover 52.

In order to keep the high tension terminal 66 30 and its circuit connecting cable 73 free from moisture and foreign matter and prevent any condensation adjacent thereto, I provide a terminal enclosing cap 75 of suitable insulating material adapted to engage the peripheral edge 76 35 of cover 52 to form a closed chamber 80. Cap member 75 is provided with suitable openings 77 and 78 through which the low tension terminals 56 and 58 project, the upper surface of the cap 75 adjacent to the low tension terminals 56 and 58 being provided with suitable depressions 79 to accommodate the circuit connection for said terminals. Located in chamber 80 and preferably filling the space within the U-shaped wall 70 is placed member 82 of resilient material, of 40 suitable dimensions and of a configuration corresponding to the space enclosed by the projecting wall 70. Resilient member 82 is provided with a semi-circular depression 83 connected to a cylindrical recess 84 both serving to accommodate the 45 terminal 66 and cable 73. As shown in Figures 4 to 7, resilient member 82 is provided at its upper surface with an upwardly projecting portion 85 and 86 to provide a good seal with cap 75 when the same is urged in position by the threaded elements or nuts 90 and 92 coacting with 50 terminals 56 and 58 which in turn retain the circuit connections 93 and 94 to the low tension windings 33.

55 In order to hermetically seal chamber 80, rubber gaskets 95 and 96 surround the terminals 56 and 58 and project into suitable recesses at the inner surface of cap 75 adjacent to opening 77 and 78. It should be noted that when the cap 75 is urged in place by tightening nuts 90 and 92 60 the resilient member 82 is compressed and the edge portion 85 and 86 tightly engage cap member 75, forcing the lateral walls of member 82 adjacent to the semi-circular groove 83 into tight engagement with the raised portion adjacent to semi-circular depression 72 formed on member 52 so that the space enclosed by wall 70 65 is completely filled by resilient member 82, as particularly shown in Figure 2.

70 It is apparent that, within the scope of the 75

invention, modifications and different arrangements may be made other than is herein disclosed, and the present disclosure is illustrative merely, the invention comprehending all variations thereof.

What I claim is:

An ignition coil including in combination, a plurality of windings enclosed by a metallic casing; a non-conducting cover forming part of said casing; terminals for said windings carried by said cover; a removable closure coacting with said cover to form a chamber enclosing a terminal for one of said windings, said removable cover being provided with openings through which terminals carried by the non-conducting

cover project, the removable cover being provided with a lateral opening through which extends the circuit connector for the terminal located within said chamber; a block of compressible rubber having an upwardly projecting peripheral rib engageable with the removable cover; said block of rubber having a semi-cylindrical groove engageable with the circuit connector for effecting a hermetical seal for said chamber; and means associated with said primary terminals for holding said removable cover in position compressing said block of rubber into intimate contact with the cover and the circuit conductor.
